UNITED STATES PATENT OFFICE.

JEWELL P. McLAURIN, OF DILLON, SOUTH CAROLINA.

POISON APPLICATOR.

Application filed May 24, 1923. Serial No. 641,179.

To all whom it may concern:

Be it known that I, JEWELL P. McLAURIN, a citizen of the United States, and a resident of Dillon, in the county of Dillon and State 5 of South Carolina, have invented certain new and useful Improvements in Poison Applicators, of which the following is a specification.

This invention relates to an improvement 10 in poison applicators of the type forming the subject-matter of my co-pending application filed Feby. 16, 1923, Serial Number 619,532 and filed March 14, 1923, Serial Number 625,084.

15 In this art, it has been found, that calcium arsenate is the most efficient if not the only effective poison adapted to be utilized for checking and killing the boll weevil. In the solutions of the arsenate which are employed 20 the calcium arsenate is only imperfectly dissolved and considerable difficulty has been experienced by reason of the fact that the solid particles of the calcium arsenate contained in the solution will build up and form 25 around the valves utilized to control the flow of the poison in poison applicators heretofore proposed.

One of the principal objects of the present 30 invention is to provide a poison applicator wherein the feed of the calcium arsenate may be completely controlled and may be so regulated as to be uniform or variable as desired and wherein at the same time the difficulty heretofore encountered in respect of the solid 35 particles of the calcium arsenate building up around the valve or other means controlling the feed is entirely overcome.

A further object is to provide a poison applicator of this character and having these 40 advantages and which has also all of the advantages and capacities of the applicators forming the subject-matter of my co-pending applications herein above referred to and which is at the same time of simple and 45 durable construction, reliable in operation, easily controlled and regulated, well balanced and adapted to be manufactured at a slight expense from materials and facilities ordinarily available.

50 Other objects and advantages of the invention reside in certain novel features of

the construction, combination and arrangement of parts which will be hereinafter more fully described and particularly pointed out in the appended claims, reference being had 55 to the accompanying drawings forming part of this specification and in which:

Figure 1 is a perspective view, illustrating the preferred embodiment of the invention;

Figure 2 is a view in section on line 2—2 60 of Figure 1;

Figure 3 is a fragmentary perspective view, showing the valve and the operating means therefor; and

Figure 4 is a fragmentary detail view in 65 section, showing the structure of the distributing pipe adjacent the valve therein.

Referring to the drawings wherein for the sake of illustration is shown the preferred embodiment of the invention, the numeral 70 10 designates generally a portable container or reservoir for the solution of calcium arsenate or poison employed. This container may be of the construction shown in either of my copending applications herein above referred to or may be of any conventional or suitable construction and for the sake of illustration is shown as including a cylindrical body portion 11 having a closed bottom 12 and having at its upper end or at the end 75 opposite its bottom a head or top 13 of frusto-conical form.

It is to be understood that the container 80 10 is portable and is to be carried around by the person applying the poison and for 85 this purpose any suitable means may be employed for facilitating the support of the container. For instance the means shown in my co-pending application herein above referred to may be employed. For the sake 90 of illustration a handle, designated at 15, is shown as secured to the body portion 11 of the container. It is to be understood that, in addition to the handle, harness or supporting straps may also be employed.

95 From the small end of the frusto-conical top 13 that is from the apex or crown portion thereof a delivery or distributing pipe 16 extends. This delivery or distributing pipe is co-axial with the container 10 and 100 communicates therewith and adjacent its outer end it is provided with a detachable

section 17 to which the mop 18 is affixed. For the sake of illustration one form of releasable or detachable connection between the section 17 and the pipe 16 is shown in Figure 4, and as shown in Figure 4 it comprises an externally threaded nipple 19 carried by the pipe 16, the pipe being provided with an internal annular shoulder 20 with which the nipple 19 is integral. The section 17 is formed with internal screw threads 21 which engage with the external screw threads of the nipple 19 to provide the detachable connection. If desired the packing 22 may be employed between the sections 17 and 18 and the pipe 16 but it is to be understood that this packing may be omitted if deemed expedient.

Means is provided for controlling and regulating the feed of the poison through the delivery and distributing pipe 16 and preferably this means includes a valve 25 of conical form and coacting with a correspondingly formed valve seat 26 machined or otherwise suitably formed on the shoulder 20. The valve 25 is pivotally mounted, as at 27, on the shoulder 20 and carries a short stem 28. The valve 25 may be adjusted and controlled so as to permit a continuous uniform flow of the desired quantity of the calcium arsenate or poison and it may be adjusted to permit of a drop by drop flow as desired and the mechanism for accomplishing this regulation or control of the valve will now be described.

As clearly shown in Figure 3 a rotatable controlled shaft 30 is provided which extends transversely through the top of the container 10, the shaft 30 being mounted in bearing sleeves 31 and 32 secured by welding, soldering or the like to the top or frusto-conical head 13. One end of the control shaft 30 projects beyond the sleeve 32 and to this projecting portion or end a control plate or finger piece 33 is pinned, as at 34, or otherwise fixed. The portion of the shaft 30 which lies intermediate the bearing sleeves 31 and 32 has mounted thereon and secured thereto a sleeve 35 which rotates with the shaft 30 and which has integrally formed therewith or rigidly secured thereto a crank arm 36. A retractile coil spring 37 has one end secured to the outer end of the crank arm 36 and has its opposite end secured to the top 13 and tends to rotate the crank arm 36 and the shaft 30 in one direction so as to tend to close the valve 25 as will presently appear. An apertured lug 38 is integrally formed with or suitably secured to the portion of the crank arm 36 which lies between its outer end and the bearing sleeve 35 and to this apertured lug an eye 39 formed on one end of a connecting rod 40 is secured, the other end of the connecting rod 40 having a similar eye 41 formed thereon and pivotally engaged or in-

terconnected with an eye 42 formed on the outer end of the short stem 28 of the valve 25.

Releasable and adjustable means is provided for holding or setting the valve 25 in adjusted position against the action of the spring 37 and preferably this means comprises a post 45 carried by the handle 15 or by any convenient support provided on the container 10 and having its outer end threaded as at 46 and loosely fitted through an elongated opening 47 provided in the control plate or finger piece 33. A knurled nut 48 is threadedly engaged with the post 46 and abuts the plate or finger piece 33.

In operation the valve 25 is controlled from the finger piece or control plate 33. Thus when the finger piece 33 is rotated in a clockwise direction, as viewed in Figures 1 and 3 the shaft 30 and its crank of this arm 36 are similarly rotated and the motion of the crank arm 36 through the rod 40 tends to swing the valve 25 about its pivot and to open the same. When the valve 25 has been opened to the desired degree the nut 48 is threaded up on the post 45 until it engages the control plate 33 and is effective to hold the control plate 33 in such position as to maintain the valve 25 open to the desired degree. In this manner the valve 25 may be held in such position to provide for drop by drop feed or for a continuous uniform flow of the desired quantity of poison. Again this flow may be varied for it is to be noted that the nut 48 and the post 45 do not prevent the control plate or finger piece 33 from being manipulated to further open the valve so that the quantity or degree of flow may be enlarged at any time as desired. This freedom of the control plate or finger piece 33 has another very important advantage in that it permits of and provides for vibration of the valve 25 to break down deposits of calcium arsenate liable to build up between the valve 25 and its seat 26 for by intermittently pressing and releasing the control plate 33, the control plate and spring 36 effect a rapid and continuous oscillation or vibration of the valve 25 whereby the deposits of solid particles of the calcium arsenate between the valve 25 and its seat 26 will be broken down.

I claim:

In a poison applicator, a container, a distributing pipe connected with the container and having a detachable section adjacent its outer end, a valve arranged in said distributing pipe adjacent said detachable connection controlling the feed of said poison through said pipe, means for controlling said valve and vibrating the same when desired including a control shaft mounted on the container and connected with the valve, a spring connected with the control shaft and tending to turn the same to such posi-

tion as to close the valve, a finger piece connected with the control shaft and adapted to be manipulated to open the valve, said finger piece having an opening, a post carried by the container and extending through the opening, said post being threaded and a nut engaged with the post and with the finger

piece for holding the finger piece in such position as to maintain the valve open to the desired degree while permitting the finger piece to be manually operated to increase the degree to which the valve is open or to vibrate the same. 10

JEWELL P. McLAURIN.
